CONTROL VALVE FOR PRESSURE BAILERS

Walter R. Hanline and James W. E. Hanes,
Ventura, Calif.

Application August 7, 1948, Serial No. 43,135

3 Claims. (Cl. 166—19)

1

Our invention relates to a control valve for pressure bailers of the type used in oil wells where it is desired to remove material from the well, such as sand, mud, sludge, or other materials.

An object of our invention is to provide a novel control valve which will effectively seal the pressure top of the bailer as the tool is being run into the well, or removed from the well.

Another object of our invention is to provide a novel control valve for pressure bailers in which the valve automatically seals the pressure top of the bailer while the bailer is being suspended in the well.

Still another object of our invention is to provide a novel control valve for pressure bailers which will seal the pressure top of the bailer, by relative longitudinal movement of the valve structure and the body of the bailer, thus controlling the venting of the pressure top to the outside.

Other objects, advantages and features of invention may appear from the accompanying drawing, the subjoined detailed description and the appended claims.

In the drawing:

Figure 1 is a partial longitudinal, sectional view of the upper portion of our pressure bailer.

Figure 2 is a partial longitudinal, sectional view of the lower part of the bailer.

Figure 3 is a partial longitudinal, sectional view of the upper part of the bailer, showing the valve in closed position.

Figure 4 is a longitudinal, sectional view of the upper part of the bailer, showing a modified form of control valve, the valve being closed.

Figure 5 is a view similar to Figure 4, and showing the valve in open position.

Referring more particularly to the drawing, our pressure bailer includes a pressure seal top 1, a plunger barrel section 2, and a dump bottom 3. A bail 4 is attached to the upper end of the pressure top 1, and a cable is attached to this bail so that the tool can be moved into or out of the well, as desired. The pressure top 1 includes an outer tube 5, into the upper end of which the bail 4 is threaded, and this bail acts as a closure for the top of tube 5 preventing flow of fluid therethrough. A fitting 6 screws into the lower end of the tube 5, and acts as a guide for the pipe 7, which extends into the tube.

A ring 8 is fixedly attached to the pipe 7, providing a shoulder 9 on the bottom thereof, which engages the shoulder 10, on the top of the fitting 6, to limit the downward movement of the pipe in the tube 5. A plurality of vent holes 11 are 55 tom of the well.

2

formed in the tube 5, for the purpose of permitting fluid to circulate outwardly from the tube 5, as shown by the arrows in Figure 1, and as will be more specifically described. A collar 12 is fixedly mounted within the tube 5, above the ports 11, and the upper end of the pipe 7 is provided with a plurality of ring packings 13, which engage the collar 12, in the lowered position of the pipe to seal off the upper pressure chamber 14. The pipe 7 extends into the top of the plunger barrel section 2 of the tool, and the plunger barrel section 2 is fixedly secured to the upper end of the dump bottom 3. The pipe 7 extends through a packing gland 7' on the top of the plunger barrel section 2, and lugs 7" on the bottom of pipe 7 prevent the pipe from pulling out of the section 2.

The construction of the plunger barrel section 2, and the dump bottom 3, is usual and well known in the art. The dump bottom 3 is open at the bottom as shown at 15, and a flap valve 16 is hingedly mounted above the bottom of the tool. The valve 16 is free to open or close, depending on whether there is pressure on the bottom or the top of the valve. The bailer is dumped by aligning the port 17, with the port 18, this being accomplished by rotating the outer part of the dump bottom until these ports match.

In operation, the tool is suspended on the cable (not shown) and the weight of the pipe 7, and the plunger barrel section 2, and dump bottom section 3, will cause the pipe to slide downwardly within the pressure top 1, until the shoulders 9, 10 abut, at which time the ring seals 13 will be within the collar 12, thus preventing the circulation of fluid out of the ports 11, while the tool is being moved downwardly in the well. As the tool is dropped, the valve 16 will be opened, and material can flow upwardly into the tool, while the tool is being lowered. When bottom is reached, or when the tool strikes a sand bridge, the pressure top 1 will slide downwardly on the pipe 7, until the packing 13 is above the collar 12. At this time, fluid can pass upwardly through the pipe, and out through the ports 11, as shown by the arrows in Figure 1. The flow of fluid through the ports 11 permits sand to be taken at the bottom of the tool, and moves upwardly past the valve 16, until the bailer is filled. Upward movement of the suspending cable will now close the ports 11, as shown in Figure 3, and the valve 16 also closes due to the weight of sand upon it. The material within the bailer is now held under the pressure of the static head at the bot-

When the surface is reached, and the ports 17, 18, are aligned, the pressure within the bailer will automatically expel the sand, and other material within the bailer. In Figures 4 and 5 is shown a modified form of packoff for the upper end of the pipe 7. In this instance we employed an expandable rubber packing ring 19, which surrounds the upper end of the pipe 7, and a collar 20 is threaded onto the upper end of the pipe and bears against the top of the packing, 19.

The lower end of the packing 19 rests on a ring 21, and this ring rests on a seat 22, above the ports 11. It is evident that downward movement of the pipe 7 would cause the packing 19, to be compressed and expand to the position shown in Figure 4. When the weight of the pipe 7, and its attached parts is relieved, the pipe 7 will move upwardly and the packing 19 will contract to the position shown in Figure 5 so that the material within the bailer can vent through the ports 11.

Having described our invention, we claim:

1. A control valve for pressure bailers, said bailer including a tubular pressure top, a plunger barrel and a dump bottom, said tubular pressure top having ports extending through the wall thereof, a pipe extending into and slidably mounted in said pressure top, and also extending through said plunger barrel and into said dump bottom, said pipe being fixedly attached at its lower end to the dump bottom, means in the pressure top engageable by said pipe to limit the longitudinal movement of said pipe in the pressure top, said pressure top including an area of reduced diameter above said ports, pack-off means on the upper end of said pipe engageable with the reduced diameter area of the pressure top to seal off said pressure top above said ports, said packoff means being of less diameter than the inside of the pressure top above said area of reduced diameter, said packoff means engaging the area of reduced diameter only on downward movement of the pipe relative to the pressure top.

2. A control valve for pressure bailers, said

bailer including a tubular pressure top, a plunger barrel and a dump bottom, said tubular pressure top having ports extending through the wall thereof, a pipe extending into and slidably mounted in said pressure top, and extending through said plunger barrel and into said dump bottom, said pipe being fixedly attached to the dump bottom, means in the pressure top engageable by said pipe to limit the longitudinal movement of said pipe in the pressure top, a collar in the pressure top above said ports, said collar being of lesser diameter than the inside diameter of the pressure top, and ring packing on the upper end of the pipe adapted to enter and seal off with the inside of the collar, to seal off said pressure top above said ports on downward movement of the pipe relative to said pressure top.

3. A control valve for pressure bailers, said bailer including a tubular pressure top, a plunger barrel and a dump bottom, said tubular pressure top having ports extending through the wall thereof, a pipe extending into and slidably mounted in said pressure top and extending through said plunger barrel and into said dump bottom, said pipe being fixedly attached to the dump bottom, means in the pressure top engageable by said pipe to limit longitudinal movement of said pipe in the pressure top, a collar fixedly mounted in the pressure top above said ports, ring packing on the pipe adapted to move longitudinally into said collar to seal off the pressure top above said ports on downward movement of the pipe relative to said pressure top.
